2,612,125

CONDITIONING NEEDLE FOR BAG
STRINGING MACHINESBertie C. Golden, Richmond, Va., assignor to
Millhiser Bag Company, Inc., Richmond, Va.,
a corporation of Virginia

Application April 5, 1950, Serial No. 154,160

7 Claims. (Cl. 112—2)

1

The invention relates to bag stringing machines, and more particularly to improvements in so-called hem nickers, piercers or conditioning needles adapted to pierce the hems of the bag being strung slightly in advance of the bag stringing needles, and thereafter to be swung laterally out of alignment with the stringing needles to bulge the hems to facilitate entry of the stringing needles, the conditioning needles being withdrawn from the hems after entry of the stringing needles.

The present application is a continuation in part of my prior applications Serial No. 515,164, filed December 21, 1943, now Patent No. 2,504,974, dated April 25, 1950, and Serial No. 792,793, filed December 19, 1947, now Patent No. 2,565,495, dated August 28, 1951, in which the conditioning needles are shown in conjunction with the stringing needles and other coacting parts of the complete stringing machine. The entire disclosures of said prior applications are hereby incorporated by reference as part of the disclosure of the present application.

An important feature of the invention resides in the fact that the conditioning needles or piercers enter and leave the hems of the bags on substantially straight lines, thus avoiding tearing of the hems or the formation of holes of large size therein. This is important for the reason that the formation of large holes would permit such free movement of the adjacent end of the drawstring as to cause it to hook or loop over the adjacent end of the mouth, causing the latter to gap open and allow tobacco to escape therefrom in the use of a filled bag. The herein described mode of operation of the piercers effectively avoids this objection.

Another feature of the invention resides in the fact that the conditioning needles or piercers are carried by elongated heads which are mounted for rectilinear movement toward and from the bags to be hemmed, and are also mounted for arcuate movement about an axis parallel to the path of rectilinear movement of the points of the conditioning needles.

Another feature of the invention resides in the use of resilient means tending to hold the points of the conditioning needles a predetermined distance apart, in substantial alignment with the bag stringing needles, whereby when the conditioning needles are moved forward in advance of the stringing needles they may be brought into accurate engagement with the bag hems.

A further feature of the invention resides in

2

the use of positive cam means for forcing the conditioning needles apart against the force of resilient means tending to hold them together, whereby the bag hems may be spread or bulged to permit the stringing needles to enter the same with facility.

Another feature of the invention resides in the shape of the heads which carry the conditioning needles or piercers, which shape enables the needles to penetrate one layer only of the cloth to facilitate entry of the stringing needles.

Hem openers

The hem openers are guided by the bag instead of a stop or other mechanical means. The rounded or inclined lead edge of the point holder exerts a cam action and slides across the hem and the point that penetrates the cloth projects from it the thickness of only one layer of cloth. By using this construction the point is always in the same relation to the bag although some bags may not be stretched down tight against the holders. If the point is not guided by the cloth, unless the bags are stretched exactly the same each time, the hem will either be missed or the point will penetrate both layers of cloth.

Another feature of the invention resides in the mounting of the conditioning needle carrying heads on reciprocable and rotatable rods or shafts mounted out of the plane of the stringing needles, thus avoiding interference with needle threading, thread clamping and other mechanism coacting with the stringing needles.

Another feature of the invention resides in the particular shape and construction of the needle carrying heads.

Other objects of the invention will be apparent from a consideration of the accompanying drawings and the following detailed description.

40 In the drawings:

Fig. 1 is a perspective view showing the bag stringing needles, the conditioning needles or piercers in their relation to a tobacco bag supported in bag stringing position, and actuating means for the stringing needles and conditioning needles, substantially as disclosed in my Patent No. 2,504,974, but with certain coacting parts of the stringing machine removed in the interest of clarity;

45 Fig. 2 is a fragmentary perspective view corresponding to the rear portion of Fig. 1, but modified in accordance with the disclosure of my Patent No. 2,565,495;

50 Fig. 3 is a plan view on a smaller scale of the construction shown in Fig. 1;

Fig. 4 is a similar plan view but modified to correspond with the disclosure of Patent No. 2,565,495;

Figs. 5, 6, 7 and 8 are fragmentary perspective views showing successive stages in the operation of the conditioning needle;

Fig. 9 is an enlarged detail perspective showing the upper portion of the conditioning needle carrying head and the needle carried thereby; and

Figs. 10 to 13 inclusive are fragmentary sectional views illustrating successive stages in the operation of the conditioning needle.

Referring to the drawings, the reference numeral 10 denotes a cloth tobacco bag or the like which, in the various figures of the drawings, is shown suspended in vertical position from a pair of corner grippers 103, 103, after the bag has been reversed, as more fully set forth in my Patent No. 2,504,974. The reversed bag at its upper or mouth portion is provided with a line of stitching 12 extending completely around the bag a little below the top thereof, which line of stitching defines the lower margin of a hem portion 13 comprising two layers of cloth between which drawstrings are to be inserted by a pair of parallel horizontally reciprocable drawstring threading needles 129, 130. The bag in its reversed position is provided with a pair of vertical side flaps 14, 14, the upper portions of which are gripped between the lips 112 and 113 of the corner grippers 103, 103 during the stringing operation, as more fully set forth in the aforesaid Patent No. 2,504,974.

The drawstring threading needles 129 and 130 are adapted to be reciprocated toward and from the suspended bag 10 in a common horizontal plane to thereby insert the drawstring in between the inner and outer layers of the bag material constituting the hem portions 13 previously referred to.

As shown, the rear ends of the bag stringing needles 129, 130 are secured to a suitable carriage 142 slidably mounted on a fixed track 600 carried by the table top 2 of the machine. Suitable fixed guides 149, 150 and 151 may be provided at intervals along the path of movement of the needles. Suitable means (not shown) are provided for threading the needles, clamping the drawstring at suitable intervals, for knotting the drawstring and cutting off the excess ends thereof, all as more fully described in the aforesaid Patent No. 2,504,974. It will also be understood that a drawstring is inserted in the bag hems in each direction of movement of the drawstring threading needles 129 and 130, but these features need not be further described in the present application as they are more fully set forth in my aforesaid patent and are not herein specifically claimed. Suitable means may be provided for reciprocating the needle carriage 142 herein shown as including a link rod 152 coupled to a bell crank lever 153, actuated from a suitable source of power, as more fully set forth in my Patent No. 2,504,974.

In order to facilitate the entry of the drawstring threading needles 129 and 130 into the hems of successive bags while suspended by the corner grippers 103, 103 a pair of hem nickers, piercers or conditioning needles 136, 136 are provided which, in accordance with the present invention, are adapted to enter and leave the hems on substantially straight lines in a direction parallel to or in alignment with the direction of movement of the stringing needles themselves. In approaching the bag to be strung, the points

1030 of the conditioning needles 136, 136 are normally spaced apart a distance about equal to but slightly less than the distance between the points of the stringing needles 129, 130, and move in advance of and in substantial alignment with the stringing needles until the conditioning needles have just penetrated the bag hems, whereupon the rectilinear movement of the conditioning needles ceases and the needles are then moved slightly outwardly, thus effecting a bulging or spreading of the layers of the hems 13 to permit the stringing needles to enter the hems with ease. After the stringing needles have entered the hems the conditioning needles are withdrawn rectilinearly in a direction parallel to the direction of movement of the stringing needles, and after the withdrawal of the stringing needles from the bag hems to a position in rear of the conditioning needles the latter are swung inwardly toward each other and are ready to resume forward movement in advance of the stringing needles in a subsequent cycle.

The mechanism for performing the above operation in accordance with the disclosure of Patent No. 2,504,974 is illustrated in Figs. 1 and 3, while similar mechanism for performing these operations in accordance with the disclosure of Patent No. 2,565,495 is fragmentarily illustrated in Figs. 2 and 4, reference being had to the disclosures of such patents for the coordinate operation of related elements of the stringing machine.

As shown, the conditioning needles 136, 136 are carried by a pair of upright needle carrying members or elongated heads 133, 133, said needle carrying members or heads being secured at their lower ends to a pair of slidable and rotatable shafts 134 mounted for reciprocation in a plane parallel to the path of movement of the stringing needles 129, 130. The shafts or rods 134 are adapted to be moved forwardly by any suitable means, such as push member 500 carried by a bell crank lever 138 actuated in timed relation to the movement of the stringing needles, as more fully set forth in my Patent No. 2,504,974. The rods 134 pass through suitable fixed guides 501, 502 carried by the frame of the machine, and each rod is provided with a collar or enlargement 503 secured thereto between which collars and the fixed guides 501 helical springs 137 are interposed, adapted to be compressed during the forward movement of the rods 134 under the influence of the positive contact member 500 carried by bell crank 138, said springs 137 serving to move the rods 134 rearwardly as the member 138 is retracted.

The rods 134 are adapted to be positively rotated in opposite directions about their respective axes in order to spread apart the points 1030 of the conditioning needles 136, 136, such positive movement being effected by means of a cam member 141 secured below the needle carriage 142 and slidably therewith. The cam member 141 is provided with a V-shaped point 504 adapted to pass between a pair of rollers 506 carried at the upper ends of upright arms or heads 143, 143 secured to rods 134, 134 near the rear thereof, the arms 143, 143 being normally urged toward one another by a tension spring 134a connecting the same. The rear upright arms or heads 143, 143 are substantially parallel to the needle carrying members or arms 133, 133 at the front ends of the rods 134, and it will be apparent that the spring 134a tends to draw the arms 143 together in the absence of the slidable cam member 141,

until the projections carried by the conditioning needle carrying heads 133 come in contact with a vertical longitudinally extending rib 1014 carried by a fixed member 1015 mounted on the frame of the machine, at which time the conditioning needles 136, 136 approach each other until their points are a distance apart which is slightly less than the distance between the points of stringing needles 129, 130 and then are in a position to enter the bag hems.

While in the arrangement shown in Figs. 1 and 3 the cam member 141 is shown attached to and movable with the needle carriage 142, the cam member 141 may if desired be slideable relative to the carriage 142 and actuated by means 141a other than the needle carriage, as illustrated for example in Figs. 2 and 4 of the present drawings, the connections between the cam member 141 and the driving shaft of the stringing machine being more fully set forth in my Patent No. 2,565,495.

While it is often desirable to provide a tension spring 134a between the upright rear arms 143 carried by the slide rods 134, this spring may be omitted and the compression springs 137 alone may be relied upon to draw the arms together. In such case the springs 137 should be so connected at their ends as to serve not only as compression members to insure rearward movement of the rods 134 and of the conditioning needle carrying heads 133 secured thereto, but also as torsion springs tending to rotate the rods 134, 134 in such a direction as to bring the inwardly projecting lugs 1013 carried by heads 133, 133 into contact with the spacing rib 1014 to keep the needle points 1030 a set distance apart when the cam member 141 is withdrawn. A tension spring (not shown) could also be provided connecting the needle carrying heads 133 instead of or in addition to the spring connecting the upright arms or members 143 carrying cam engaging rollers 506.

Another feature of the invention resides in the construction of the members or heads 133 which carry the conditioning needles or piercers 136. As previously set forth, these members are of substantial height so that their rods or shafts 134 may be located a substantial distance out of the plane of the operation of other mechanism co-operating with the stringing needles, such as needle threading mechanism, thread clamping mechanism, etc.

The inner or facing surfaces 1000 of the pair of needle carrying heads 133 are inclined forwardly and inwardly, as indicated in Figs. 9 to 13, and the conditioning needles 136, 136 are similarly inclined. These needles are adjustably mounted in their respective heads by means of set screws 1001, whereby the positions of the points of the conditioning needles may be accurately located. Adjacent the needle points the heads are hollowed out as indicated at 1002. Beyond the hollowed out portion 1002 the head is provided with a rounded or inclined tip portion 1003. In adjusting the needle a needle tip is brought into substantial alignment with the extremity of the tip portion 1003 so that in rubbing the finger along the face of the head 133 the tip of the needle will scarcely be felt, if at all. The two opposite heads 133, 133 carrying the conditioning needles while approaching the bag supported by the corner grippers are so close together that the tip portions 1003 of the heads will slightly compress the hem portions of the bag in passing over the same, but owing to the resiliency of the material such

material will spring back into the hollowed out portion of the head 1002 adjacent the needle tip, enabling said needle tip to engage the outer layer only of the bag making material without contacting the inner layer. This is clearly indicated in Fig. 11.

As shown, each of the heads 133 includes lower and upper portions 1010 and 1011 with a reduced connecting portion 1012 formed by a transversely extending cut-away portion 1023. The lower portion 1010 is detachably secured to the rod or shaft 134 by means of a set screw 1004.

As previously set forth, the inner surface 1000 of each head is inclined inwardly and forwardly, and the needles 136, 136 carried by posts 1006 at the upper portions of said heads are similarly inclined. Adjustment of the needles in their respective heads is provided by means of the set screws 1001 extending downwardly through the posts 1006 whereby the positions of the points 1030 of the conditioning needles may be accurately located. Spaced forwardly of the post 1006 and separated therefrom by a cut-out portion 1008 is a second post 1009, in which is provided the smooth hollowed out portion or groove 1002 previously referred to, which extends generally in the direction of the needle point 1030 and terminates just short of the rounded front edge or nose portion 1003 of the needle carrying head 133. Each head 133 is also preferably provided with an inwardly projecting lug or stop member 1013 which is adapted to coact with the upstanding rib 1014 of the spacing member 1015 to limit the inward movement of the upper portion of the head 133 under the influence of the tension spring 134a. The post 1006 of the head 133 is preferably provided with a horizontally extending groove 1016 to provide clearance for the stringing needles 129, 130 so that the stringing needles will not jam against the backs of the holders 133 before the conditioning needles are spread apart. The stringing needles follow closely behind the conditioning needles 136 and the points of the stringing needles ride in these grooves as the conditioning needles are spread apart.

The operation of the conditioning needles 136 in their relation to the stringing needles 129, 130 will in general be apparent from the foregoing description. As previously stated, tension spring 134a connecting the rear heads 143 mounted on the rods 134 carrying the conditioning needle heads 133 at their front ends normally serves to rotate the rods 134 toward one another, the inward rotation being stopped by engagement of the lugs 1013 carried by heads 133 with the upstanding rib 1014 of the spacing member 1015. At this stage the points 1030 of the conditioning needles will be spaced apart a distance about equal to but very slightly less than the distance between the points of the stringing needles 129 and 130, and at the beginning of the cycle to be described the points of the conditioning needles will be in advance of and in substantial alignment with the points of the stringing needles. Prior to the time that the stringing needles are moved forward to engage the bag hems the conditioning needles are moved forward by contact of the push member 500 carried by the bell crank 138 with the rear ends of the rods 134, thus advancing said rods, carrying with them the heads 133 and conditioning needles 136, and at the same time compressing springs 137 between collars 503 and the fixed guide members 501 through which the rods 134 pass. The heads

133 carrying the needles 136 at their upper portions move forwardly in a rectilinear path guided by sliding contact between the lugs 1013 and the longitudinal guide rib 1014 until the rounded nose or leading edge 1003 at the front of the head comes in contact with an outer layer 1020 of the bag 10, whereupon the nose 1003 rides on the bag, forcing the head 133 slightly outwardly against the tension of spring 134a and bringing the point 1030 of the conditioning needle exactly into position to engage the bag hem between outer and inner layers 1020 and 1021 of the cloth. Thus, the position of the point of the conditioning needle from the time the leading edge 1003 of the head 133 contacts the bag until the conditioning needle point 1030 itself reaches the bag is guided by the bag material rather than by mechanical means that could develop play or wear. Accordingly, entry of the point of the conditioning needle at exactly the right position is assured. Forward movement of the push member 500 and rods 134 ceases when the points 1030 of the conditioning needles have entered the bag hems, but said push member remains in contact with the rods 134 to prevent rearward movement until the cam point 504 of the slide member 141 has engaged the rollers 506 carried by heads 143 to rotate the rods 134 and needle carrying heads 143 slightly outwardly, thereby causing the points of the conditioning needles to be swung slightly outwardly in an arcuate path and bulging the hems of the bags to allow the stringing needles 129 and 130 to enter. The cut-out portions 1002 in the heads 133 adjacent the points 1030 of the conditioning needles enable the cloth of the hem to slide upon the conditioning needles as indicated in Fig. 11. Forward movements of the stringing needle carriage 142 and cam slide 141 commence shortly after the conditioning needles begin to move forwardly and the stringing needles should follow closely behind the conditioning needles; the points of the stringing needles riding in the grooves 1016 in the rear of the heads 133 as the conditioning needles are spread apart to bulge the bag hems and permit the stringing needles to enter the bulged portion. After the stringing needles have entered the bag hems the conditioning needles, which are now spread apart by the cam point 504 on the front side of slide 141, are retracted by the springs 137 on the reverse movement of the push rod 500 carried by bell crank 138. This reverse movement is in a rectilinear path parallel to the forward movement of the conditioning needles in entering the bag. After the stringing needles have been withdrawn from the bag at the conclusion of the stringing operation the sliding cam member 141 is also withdrawn, thus allowing the spring 134a connecting the members 143, 143 to return the conditioning needles to normal position with the lugs 1013 carried by heads 133 contacting opposite sides of the spacer 1014 preparatory to the commencement of the next stringing cycle. The cut-out portions 1008 in the heads 133 carrying the conditioning needles provide space adjacent the conditioning needles so that lint and thread from the bags will not accumulate and prevent the needles from functioning properly. The cut-out portions 1023 may serve a similar function.

The invention has been described in detail for the purpose of illustration, but it will be obvious that numerous modifications and variations may be resorted to without departing from the spirit of the invention. For example, any suitable means may be provided for rotating

the needle carrying heads 133 in opposite directions at suitably timed intervals. Also, any suitable means for limiting the movement of the heads toward one another may be provided. 5 Thus, the rollers 506 carried by the rear heads 143 could be made of such size as to contact one another when the points of the conditioning needles are in their innermost positions. Other variations may be apparent to those skilled in the art.

I. claim:

1. A bag stringing machine, including a reciprocable bag stringing needle, means for supporting a hemmed bag in stringing position with its hem in alignment with said stringing needle, means for imparting rectilinear movement to said needle to insert a drawstring in the hem of the bag, a reciprocable conditioning needle adapted to be moved toward and away from the bag in a direction in substantial alignment with or parallel to the direction of movement of the stringing needle, and arranged to be rocked in an arcuate path toward and away from the path of movement of the stringing needle, means for reciprocating the conditioning needle toward and away from the supported bag, and means for arcuately rocking the conditioning needle into and out of alignment with the stringing needle, said conditioning needle being carried by a head mounted on a rotatable and reciprocable rod spaced from but in the same vertical plane as the stringing needle.

2. A bag stringing machine, including means for supporting a hemmed bag in stringing position, a bag stringing needle, means for imparting rectilinear movement to said stringing needle to insert a drawstring in the hem of the bag, and a conditioning needle, adapted to penetrate the bag hem prior to the insertion of the stringing needle, in substantial alignment with the stringing needle; then to be rocked arcuately out of the path of the stringing needle to bulge the hem and to facilitate entry of the stringing needle; and subsequently to be withdrawn in a direction parallel to the direction of movement of the stringing needle, means for reciprocating the conditioning needle toward and away from the bag hem, and means for rocking the conditioning needle arcuately into and out of the path of the stringing needle, said conditioning needle being carried by a head mounted on a rotatable and reciprocable rod spaced from but parallel to the stringing needle, and reciprocable in a path parallel thereto.

3. A bag stringing machine as set forth in claim 2, wherein the last named means includes positive means for swinging the head carrying the conditioning needle outwardly away from the path of the stringing needle, resilient means urging the head in the opposite direction, and fixed guide means for limiting the inward movement of the head under the influence of said resilient means.

4. A bag stringing machine including a horizontally reciprocable bag stringing needle, means for supporting a hemmed bag with its hem in alignment with the stringing needle, means for reciprocating the stringing needle to insert a drawstring in the hem of the bag, and a conditioning needle adapted to penetrate the bag hem prior to the insertion of the stringing needle in alignment therewith, then to be rocked arcuately out of the path of the needle, and to be subsequently withdrawn in a direction parallel to the direction of entry, a head carrying said con-

ditioning needle, a reciprocable and rotatable rod carrying said head, and movable in a rectilinear path spaced from but parallel to the path of movement of the stringing needle, means for reciprocating said rod in timed relation to the stringing needle, resilient means tending to rotate the rod in one direction and positive means for rotating the rod in the opposite direction against the force of said resilient means.

5. In a bag stringing machine, means for suspending a hemmed bag in stringing position, including a pair of internal corner grippers engaging the bag at opposite ends of the hem mouth thereof, a bag stringing needle, means for imparting rectilinear movement to the stringing needle and a conditioning needle adapted to penetrate the bag hem in advance of the stringing needle and in alignment therewith, then to be rocked arcuately out of the path of the stringing needle to bulge the hem and facilitate entry 15 of the stringing needle, and subsequently to be withdrawn in a direction parallel to the direction of entry, an elongated head carrying said conditioning needle, and a rotatable and reciprocable rod carrying said head, mounted for reciprocation in a direction parallel to but spaced from the stringing needles but in the same vertical plane therewith, said conditioning needle being mounted in said head near the opposite end thereof from the point of attachment to said rod, said head being recessed to receive the point of 20 said needle, and having an inclined or rounded front cam portion in advance of and substantially in alignment with the conditioning needle point, said front portion being adapted to momentarily compress the material of the bag in advance of the conditioning needle as the head is moved forwardly, and to permit the material to bulge into the recess of said head after the front portion has passed thereover, thereby permitting the needle point within said recess to engage the bulged hem portion.

6. In a bag stringing machine, means for suspending a hemmed bag in stringing position, including a pair of internal corner grippers engaging the bag at opposite ends of the hem mouth thereof, a bag stringing needle, means for imparting rectilinear movement to the stringing needle and a conditioning needle adapted to penetrate the bag hem in advance of the stringing needle and in alignment therewith, then to be rocked arcuately out of the path of the stringing needle to bulge the hem and facilitate entry 45 of the stringing needle, and subsequently to be withdrawn in a direction parallel to the direction of entry, an elongated head carrying said

conditioning needle, a rotatable and reciprocable rod carrying said head, mounted for reciprocation in a direction parallel to but spaced from the stringing needles but in the same vertical plane therewith, said conditioning needle being mounted in said head near the opposite end thereof from the point of attachment to said rod, said head being recessed to receive the point of said needle, and having an inclined or rounded front cam portion in advance of and substantially in alignment with the conditioning needle point, said front portion being adapted to momentarily compress the material of the bag in advance of the conditioning needle as the head is moved forwardly, and to permit the material to bulge into the recess of said head after the front portion has passed thereover, thereby permitting the needle point within said recess to engage the bulged hem portion, and means for accurately adjusting the position of the point of the conditioning needle within the recess in said head.

7. A bag stringing machine including a pair of stringing needles, means for supporting a hemmed bag in stringing position in alignment with said needles, means for imparting rectilinear movement to said needles to insert drawstrings in the hems of the bag, a pair of conditioning needles adapted to be reciprocated toward and away from the bag in a direction in substantial alignment with or parallel to the direction of movement of the stringing needles, and arranged to rock in an arcuate path toward and away from the path of movement of the stringing needles, 25 means for reciprocating the conditioning needles toward and away from the supported bag, and means for arcuately rocking the conditioning needles into and out of alignment with the stringing needles, said stringing needles being reciprocable in a horizontal plane, and the conditioning needles being carried by heads mounted on a pair of rotatable and reciprocable rods parallel with the stringing needles but located in a different horizontal plane from the stringing needles.
